Term of patent 14 years

Int. Cl. D21—01

U.S. Cl. D34—15

FIG. 1 is a side elevational view of a novelty amusement device as viewed along the line 1—1 of FIG. 3 showing my new design;

FIG. 2 is another elevational view, as viewed along the line 2—2 of FIG. 3, of the device shown in FIG. 1;

FIG. 3 is a top plan view, as viewed along the line 3—3 of FIG. 1, of the device shown in FIGS. 1 and 2;

FIG. 4 is a top plan view, similar to FIG. 3, of the device shown in FIGS. 1—3, but differing from FIG. 3 in that the pair of slidable members and crank are shown in a different selected position; and,

FIG. 5 is a top plan view, similar to FIGS. 3 and 4, of the device shown in FIGS. 1—4, but differing from each of FIGS. 3 and 4 in that the pair of slidable members and crank are shown in a third selected position.

I claim:

The ornamental design for a novelty amusement device, as shown and described.
